REFLECTOR

Yosimasa Tsuyama, Higash Sumiyoshi-ku, Osaka, Japan,
assignor to Tsuyama Mfg. Co., Ltd., Higashi Sumiyoshi-
ku, Osaka, Japan

Filed Nov. 21, 1974, Ser. No. 525,805

Claims priority, application Japan Sept. 19, 1974

Term of patent 14 years

Int. Cl. D10—06

U.S. Cl. D10—111

FIG. 1

FIG. 2

FIG. 3

FIG. 1 is a front, top and right side perspective view of a reflector showing my new design;

FIG. 2 is a right side elevational view thereof, the left side being the mirror image thereof; and

FIG. 3 is a bottom plan view thereof.

The rear of the reflector is identical to the front, with the exception of the angle of flare of the mounting ears.

I claim:

The ornamental design for a reflector, as shown and described.
